UNITED STATES PATENT OFFICE.

TERENCE J. GOODWIN, OF SYRACUSE, NEW YORK.

PATTERN FOR DRAFTING SHIRT-BOSOMS.

SPECIFICATION forming part of Letters Patent No. 501,339, dated July 11, 1893.

Application filed March 11, 1893. Serial No. 465,558. (No model.)

To all whom it may concern:

Be it known that I, TERENCE J. GOODWIN, of Syracuse, in the county of Onondaga, in the State of New York, have invented new and 5 useful Improvements in Shirt-Patterns, of which the following, taken in connection with the accompanying drawings, is a full, clear, and exact description.

My invention relates to improvements in 10 patterns for drafting the bosom-pieces of shirts, and has for its object the production of a practical, simple, durable, and effective device consisting of adjustable plates or sections capable of ready adjustment for facilitating the drafting of a well fitting bosom-piece for shirts.

The invention consists in the detail construction and arrangement of the parts, all as hereinafter more particularly described and 20 pointed out in the claims.

In describing this invention, reference is had to the accompanying drawings, forming a part of this specification, in which like letters and figures indicate corresponding parts in all the 25 views.

Figure 1 is a face view of my improved pattern. Fig. 2 is a similar view representing the pattern as somewhat distended, and Fig. 3 is a sectional view, taken on line —3—3—, 30 Fig. 2.

My present invention consists of a pattern, which is readily adjustable to any required size of bosom-piece for enabling an operator to readily and correctly draft a bosom-piece of 35 the required size without the exercise of a high degree of skill. This pattern consists of the lengthwisely adjustable plate —A— for regulating the length of the central portion of the bosom-piece, a top plate composed of length-40 wisely adjustable arms —B—B— extending laterally from one end of the plate —A— for regulating the width of the upper end of the bosom-piece, a bottom plate consisting of lengthwisely adjustable arms —C—C— extending laterally from the opposite end of the 45 plate —A— for regulating the width of the lower end of the bosom-piece, and the lengthwisely adjustable side plates —D—D— having their upper ends secured to the outer ends 50 of the arms —B—B— and their opposite ends secured to the corresponding ends of the arms —C—C— for regulating the length and con-

tour of the longitudinal sides of the bosom-piece.

The plate —A— consists of the sections 55 —a—a'— having their inner or adjacent ends lapped one upon the other and provided with lengthwise slots —a²—a³—. A suitable lug —e— is secured to the lower or inner end of the section —a'—, and is formed with a shank 60 —e'— registered with the slot —a²— in the section —a—, and with a shoulder —e²— bearing against the under face of said section —a—. This lug serves to guide the sections —a—a'— in their lengthwise movement, and 65 this guiding action is facilitated by the shank —f— of the clamp —F—, which may be of any desirable construction for clamping said sections —a—a'— in their adjusted position and aiding in guiding said sections in their 70 adjustable movement.

As best seen at Fig. 3 the shank —f— of the clamp —F— is passed through an opening —a⁴— in the upper or inner end of the section —a—, is registered with the slot —a³— 75 of the section —a'—, and is provided at one end with a shoulder —f'— bearing against the under face of the section —a—. A nut —f²— is movable on the opposite end of the shank —f— and bears against the upper face 80 of the section —a'—.

The section —a— of the plate —A— is provided with a scale —1—, along which is movable the lower edge —a⁵— of the section —a'—. This scale —1— is formed with graduations 12½, 13, 14, &c., to 18 extending from the lower end of the section —a— toward its central portion, and serves to regulate the length of the central portion of the bosom-piece. It will thus be readily apparent that 90 the plate —A— is quickly adjusted lengthwisely until the desired graduation is exposed beneath the edge —a⁵— of the section —a'—, and that these sections —a—a'— are then held positively and effectively in their adjusted 95 position by the clamp —F—.

The arms —B—B— for regulating the width of the upper end of the bosom-piece each consists of sections —b—b'—, the sections —b—b— being fixedly secured to the upper 100 end of the plate —A— in any desired manner as by rivets —b²— and the sections —b'—b'— being movable lengthwisely upon the sections —b—b—. The sections —b—b'— of each

arm —B— are provided with lengthwise slots — b^4 —, and the inner end of the section — b' — of each arm —B— is provided with a lug —e—, which is registered with the slot — b^4 — in the 5 corresponding section —b—, and is of the same construction as the lug —e— previously described. The outer end of each section —b— is provided with the clamp —F— similar to the clamp —F— previously described, and this 10 latter clamp —F— is movable lengthwise in the slot — b^4 — in the corresponding section — b' —, and serves to firmly secure together the sections of the arm —B— provided therewith when said sections are adjusted to their 15 desired position. Each of the sections —b— is provided with a scale —2— along which is movable the inner edge — b^5 — of the corresponding section — b' —, and these scales are provided with graduations —7— —8— and 20 —9— extending outwardly from the inner ends of said sections —b—.

The arms —C—C— for regulating the width of the lower end of the bosom-piece are each composed of sections —c—c'—, the sections 25 —c—c— being fixedly secured to the opposite or lower end of the plate —A— in any desired manner, and the sections —c'—c'— being movable lengthwise upon the sections —c—c—. The sections —c—c— are prefer- 30 ably formed integral with the lower end of the section —a— of the plate —A— as best seen at Fig. 2. These arms —C—C— are of less length than the arms —B—B—, and the sections —c'—c'— thereof are provided with 35 lengthwise slots — c^4 —. The outer end of each of the sections —c— is provided with a clamp —F— similar to the clamp —F— previously described, and said clamps serve to firmly secure the sections —c'— to said sections —c—. Each of the sections —c— is pro- 40 vided with a scale —3—, along which is movable the inner edge — c^5 — of the corresponding section —c'—, and these scales are pro- 45 vided with graduations —7— —8— and —9— extending outwardly from the inner ends of 50 said sections —c—c—. It will thus be readily understood that the arms —B—B—C—C— project from the plate —A— in planes at substantially right angles therewith, and are ad- 55 justed lengthwise in planes at substantially right angles to the plane of adjustment of the plate —A—, and consequently the longitudinal edges of said arms —B—B—C—C— are substantially perpendicular to the correspond- ing edges of the plate —A—.

The plates —D—D— for regulating the length and the inclination of the sides of the bosom-piece are each of similar construction, and are composed of sections —d—d'—, the 60 sections —d— of each plate —D— being secured to the outer end of the section — b' — of the corresponding arm —B—, and the section —d'— being secured to the outer end of the section —c'— of the corresponding arm 65 —C—.

As preferably constructed the upper end of the section —d— of each plate —D— is hinged

70 by a suitable pivotal pin — d^2 — to the outer end of the section — b' — of the corresponding arm —B—, and the lower end of the section —d'— is preferably formed integral with the section —c'— of the corresponding arm —C—. The adjacent or inner ends of the sections —d—d'— are formed with lengthwise slots — d^4 —, and movable in said slots are two 75 lugs —e—e—, which are of similar construction to the lugs —e— previously described, and are secured respectively to the lower end of the section —d— and to the upper end of the section —d'—. The longitudinal edges 80 of the lower ends of the sections —d—d'— of the plates —D—D— are curved inwardly for giving the desired contour to the bottom portions of the longitudinal edges of the bosom-piece when drafted by marking around the 85 edge of my improved pattern.

It will be readily understood by one skilled in the art that, as the plate —A— is adjusted lengthwise in conformity with the desired length of the bosom-piece, the side plates 90 —D—D— are also adjusted lengthwise, and that their sections —d—d— swing upon the pivotal pins — d^2 — for facilitating the ready adjustment of my improved pattern.

In order that my invention may be readily 95 understood I have shown the same at Fig. 2 as adjusted for a bosom-piece of a shirt bosom fifteen inches long and nine inches wide. Consequently the division —15— is exposed beneath the lower edge — a^5 — of the 100 section —a'—, and the divisions —9— are exposed at the inner sides of the edges — b^5 — c^5 — of the sections —b'—c'— at the opposite ends of the plate —A—.

My pattern may be similarly adjusted to 105 any other measurement of the bosom-piece, and, after the pattern is adjusted, the bosom-piece may be readily drafted by placing the pattern upon the fabric and marking around the outer edge of said pattern. It is apparent that one of the arms —B—, the corresponding arm —C—, and the interposed side plate —D— may be dispensed with, and that the bosom-piece can then be readily drafted by folding the fabric and placing the folded edge 110 directly beneath the longitudinal center line of the lengthwise plate —A—, and by then marking around the edges of the remaining plate —D— and the arms —B—C—. It is also evident that, if desired, the central plate 115 —A— may be dispensed with, and the sections —b'—c'— of the arms —B—C— may then be supported directly upon the sections —b—c— of said arms, which, as previously 120 stated, are secured to the lengthwise adjustable side plates —D—D—. This is, however, no material modification of my invention.

The operation of my invention will be readily perceived from the foregoing description 130 and upon reference to the drawings, and it will be particularly noted that the same is simple, practical, durable, and effective.

Having thus fully described my invention,

what I claim as new, and desire to secure by Letters Patent, is—

1. The herein described pattern for the bosom-piece of a shirt, the same comprising a lengthwisely adjustable plate —A—, having a substantially straight longitudinal edge an arm —B— extending laterally from one end of the plate —A— and consisting of sectionslapping with each other and adjustable lengthwisely in a plane at substantially right angles to the plane of adjustment of the plate —A— one of said sections being fixedly secured to the plate A, an arm —C— extending laterally from the opposite end of the plate —A— and consisting of sectionslapping with each other and adjustable lengthwisely in a plane at substantially right angles to the plane of adjustment of the plate —A— one of said sections being fixedly secured to the plate —A—, and a lengthwisely adjustable side plate —D— having one extremity secured to the outer end of the arm —B— and the other extremity secured to the corresponding end of the arm —C— and formed with a longitudinal edge turned inwardly, substantially as and for the purpose set forth.

2. The herein described pattern for the bosom-piece of a shirt, the same comprising a lengthwisely adjustable plate having a substantially straight longitudinal edge, and composed of a section —a— provided with a scale —1— and a section —a'— movable lengthwisely of said scale —1—, a lengthwisely adjustable arm —B— extending laterally from one end of the plate —A— and composed of a section —b— fixedly secured to said end of the plate —A— and provided with a scale —2—, and a section —b'— movable lengthwisely of the scale —2—, a lengthwisely adjustable arm —C— extending laterally from the opposite end of the plate —A— and composed of a section —c— fixedly secured to said opposite end of the plate —A— and provided with a scale —3—, and a section —c'— movable lengthwise of the scale —2—, and a lengthwisely adjustable plate —D— having one extremity secured to the outer end of the arm —B— and the other extremity secured to the corresponding end of the arm —C— and formed with a longitudinal edge curved inwardly, substantially as specified.

3. The herein described pattern for the bosom-piece of a shirt, the same comprising a lengthwisely adjustable plate —A—, an upper plate composed of arms —B—B— extending laterally from opposite sides of one end of the plate —A— and each consisting of sectionslapping with each other and adjustable lengthwisely in a plane at substantially right angles to the plane of adjustment of the plate —A— one of the sections of each of said arms being fixedly secured to the plate A, a lower plate composed of arms —C—C— of less length than the arms —B—B— extending laterally from opposite sides of the opposite end of the plate —A— and each consisting of sectionslapping with each other and adjust-

able lengthwisely in a plane at substantially right angles to the plane of adjustment of the plate —A— one of the sections of each of said arms being fixedly secured to the plate A, and lengthwisely adjustable side plates —D—D— having corresponding extremities secured to the outer ends of the arms —B—B— and having their opposite extremities secured to the corresponding ends of the arms —C—C— and each formed with a longitudinal inwardly turned edge, substantially as described.

4. The herein described pattern for the bosom-piece of a shirt, the same comprising a lengthwisely adjustable plate composed of a section —a— provided with a scale —1— and a section —a'— movable lengthwisely of said scale —1—, an upper plate composed of arms —B—B— extending laterally from opposite sides of one end of the plate —A—, said arms being each composed of a section —b— fixedly secured to one end of the plate —A— and provided with a scale —2— and a section —b'— movable lengthwisely of the scale —2—, a lower plate composed of arms —C—C— of less length than the arms —B—B—, said arms being each composed of a section —c— fixedly secured to the plate —A— and provided with a scale —3— and a section —c'— movable lengthwisely of the scale —2—, and lengthwisely adjustable side plates —D—D— having corresponding extremities secured to the outer ends of the arms —B—B— and having their opposite extremities fixedly secured to the corresponding ends of the arms —C—C—, said opposite extremities of the side plates —D—D— having longitudinal edges curved inwardly, substantially as set forth.

5. The herein described pattern for the bosom-piece of a shirt, the same comprising lengthwisely adjustable arms —B—B— each having a substantially straight longitudinal edge, lengthwisely adjustable arms —C—C— disposed in a plane substantially parallel with that of the arms —B—B— and each having a substantially straight longitudinal edge, and lengthwisely adjustable side plates —D—D— having corresponding ends secured to the outer ends of the arms —B—B— and having their opposite ends secured to the outer ends of the arms —C—C— and provided with longitudinal edges having their upper portions substantially perpendicular to the substantially straight longitudinal edge of the arms —B—B— and having their lower ends curved inwardly, as and for the purpose specified.

In testimony whereof I have hereunto signed my name, in the presence of two attesting witnesses, at Syracuse, in the county of Onondaga, in the State of New York, this 27th day of February, 1893.

TERENCE J. GOODWIN.
